UNITED STATES PATENT OFFICE.

HARRIE A. RIPLEY, OF WESTDALE, MASSACHUSETTS.

TROLLEY-HARP.

SPECIFICATION forming part of Letters Patent No. 739,223, dated September 15, 1903.

Application filed January 26, 1903. Serial No. 140,613. (No model.)

To all whom it may concern:

Be it known that I, HARRIE A. RIPLEY, a citizen of the United States, residing at Westdale, in the county of Plymouth and State of Massachusetts, have invented certain new and useful Improvements in Trolley-Harps, of which the following is a specification.

This invention relates to trolleys for electric-car systems of the overhead type, the purpose being to devise novel means to admit of the trolley-wheel turning with reference to the pole, so as to readily adapt itself to any deviation from a straight course; to interpose springs in a peculiar manner between the head or fork and the body of the harp and protect the same from injurious contact with the line-wire in the event of the trolley leaving the same from any cause; to mount the trolley-wheel so as to minimize the friction; to insure a positive connection between the trolley-wheel and harp, whereby the current is continuous, and, lastly, to provide a device which will operate satisfactorily, admit of repairs being quickly and cheaply made, and in which all the parts are accessible for any purpose.

For a full description of the invention and the merits thereof and also to acquire a knowledge of the details of construction of the means for effecting the result reference is to be had to the following description and drawings hereto attached.

While the essential and characteristic features of the invention are susceptible of modification, still the preferred embodiment of the invention is illustrated in the accompanying drawings, in which—

Figure 1 is a side elevation of a trolley-harp embodying the invention. Fig. 2 is a top plan view. Fig. 3 is a vertical transverse section about on the line X X of Fig. 1 looking to the right, as indicated by the arrow. Fig. 4 is a detail perspective view of the spring connection forming an electric conductor between the trolley-wheel and the head. Fig. 5 is a side view of the trolley-wheel and bushing arranged therein and keyed thereto.

Corresponding and like parts are referred to in the following description and indicated in all the views of the drawings by the same reference characters.

The harp or trolley-frame is composed, es-

sentially, of two parts, a head or fork 1 and a body 2, the latter comprising a vertical bearing 3 and a stem 4, arranged at an angle with reference to the bearing 3 and made tubular, so as to receive the upper end of the trolley-pole (not shown) to which the trolley-harp may be fitted. Clamp-screws 5 are threaded into bosses formed at the sides of the stem 4 and are adapted to secure the harp or frame to the trolley-pole in an adjusted position, thereby admitting of the frame being disconnected or applied to the pole at will. An eye 6 is arranged at the lower side of the stem 4 to receive the rope or cord by means of which the trolley is operated in the accustomed way.

The head or fork 1 has a journal 7 at its lower end mounted in the bearing 3 and held therein by means of a pin 8, threaded or otherwise secured in a side of the bearing 3 and extended into a recess 9, formed in a side of the journal 7. The recess 9 is of a circumferential extent to admit of the head or fork 1 having a limited movement in each direction. The journal 7 is hollow by preference, so as to receive and contain a quantity of oil, by means of which the bearing 3 is lubricated, oil being supplied to the bearing by means of an opening 10, formed in a side thereof near the upper end. The fork sides or members are thickened at their upper ends, as shown at 11, and are vertically slotted, as shown at 12, the thickened portions 11 forming reinforcements and being recessed in their outer sides to receive washers 13 and nuts 14, co-operating with the threaded ends of the axle 15, upon which the trolley-wheel 16 is mounted. The head 1 and stem 4 are kept in alinement by means of a pair of springs 17, which are of the coil type and constructed of spring-wire sufficiently stout to hold the parts from playing too freely. The coil-springs 17 are connected at one end to a stud 18, projected upward from the outer or rear portion of the stem 4, and are made fast at their upper forward ends to the crown of the fork or head 1 at opposite sides thereof, the springs being upwardly and forwardly diverged.

To prevent injurious contact of the springs 17 with the trolley-line in the event of the trolley-wheel leaving the same, a guard 19 is provided and consists of a plate located above the stem 4 and in advance of the trolley-wheel,

- said plate being flared and slightly curved transversely and having the side end adjacent to the trolley-wheel made concave to admit of the flanges of said wheel projecting beyond a straight line touching the horns of the guard. A post 20 is secured to or formed with the stem 4 and supports one end of the guard 19, the opposite end of said guard being secured to a lug 21, formed upon the top side 5 of the stem 4 adjacent to its outer or rear end. The trolley-wheel 16 is peripherally grooved and its sides made hollow and strengthened by ribs or flanges 22. A bushing 23 is fitted within the hub of the trolley-wheel and is secured therein against rotation by means of a key 24^a, slipped into seats formed in corresponding portions of the bushing and hub. The opening of the bushing is enlarged at its ends to receive ball-bearings comprising cups 24, cones 25, and balls 26. The axle 15 passes through the bushing, and its threaded ends drop into the slots 12 in the thickened or reinforced ends of the fork and receive washers 13 and nuts 14, by means of which the parts 10 are secured. Upon loosening the nuts 14 the trolley-wheel may be readily disconnected from the fork or applied thereto, as will be readily comprehended, the slots 12 facilitating this operation.
- 15 To preserve and maintain a continuity of the circuit under all conditions, a spring-conductor has been devised and interposed between the trolley-wheel and fork, so as to make direct electrical connection with each.
- 20 As shown, the spring-conductor 27 is approximately of U form and is secured at one end to the fork by means of a clamp-screw 28 and is provided at its opposite end with a shoe 29 in frictional engagement with the peripheral portion of the trolley-wheel intermediate of the flanges. The conductor 27 is located in the crotch of the fork and in the space formed between the flanges of the trolley-wheel.
- 25 Having thus described the invention, what is claimed as new is—

1. In a trolley, the combination of a harp comprising a body portion and a fork, the latter journaled to said body and having a limited lateral turning, a spring connection between the said fork and body, and a guard secured to said body in advance of the trolley-wheel and above the spring connection and comprising a flared plate, substantially as set forth. 50

2. In a trolley for electric-car systems, the combination of a body portion and fork relatively journaled, coil-springs secured at one end to the body and at the opposite end to opposite sides of the fork, a lug and post projected upward from the stem of the body, and a guard secured to said lug and post and flared throughout its length and transversely curved between its edges, the wide end adjacent to the trolley-wheel being made concave, substantially as set forth. 60

3. In a trolley for electric-car systems, a fork having the end portions of its side members thickened or reinforced, recessed in their outer sides and slotted, an axle having its end portions fitted in said slots, a trolley-wheel mounted upon the axle, and washers and nuts applied to the threaded ends of the axle and adapted to enter the recesses in the outer sides of the reinforced fork ends, substantially as specified. 70

4. In a trolley for electric-car systems and in combination with the harp, a trolley-wheel journaled thereto, an electric spring-conductor secured at one end comprising a spring of approximately U form, said spring being secured at one end to the harp and having a contact-shoe disposed at the opposite end and adapted to bear against the trolley-wheel, the end portions of said shoe being rounded, substantially as set forth. 80

In testimony whereof I affix my signature in presence of two witnesses.

HARRIE A. RIPLEY. [L. S.]
